UNITED STATES PATENT OFFICE.

CHARLES E. EGAN, OF LAFOLLETTE, TENNESSEE, ASSIGNOR TO JOHN M. SCHUSTER, OF COLUMBUS, OHIO.

COMBINED ELECTRIC DOOR-BELL AND FIRE-ALARM.

1,011,175.

Specification of Letters Patent.

Patented Dec. 12, 1911.

Application filed October 26, 1910. Serial No. 589,093.

To all whom it may concern:

Be it known that I, CHARLES E. EGAN, a citizen of the United States, residing at Lafollette, in the county of Campbell and State of Tennessee, have invented certain new and useful Improvements in Combined Electric Door-Bells and Fire-Alarms, of which the following is a specification.

My invention consists in the improved construction of a combined electric door bell and fire alarm.

The objects of my invention are to combine with an ordinary electric house bell, means for ringing the bell automatically through the action of heat; to so construct my improved alarm and door bell as to admit of the same being produced at a comparatively low cost of manufacture and to provide means for adjusting the heat controlled diaphragm for operation by different temperatures. These objects I accomplish in the manner illustrated in the accompanying drawings, in which—

Figure 1 is a face view of my improved device, showing a diagrammatic illustration of the wiring outside of the bell ringing device, and Fig. 2 is a sectional view on two planes as indicated by line $x-x$ on Fig. 1.

Similar numerals refer to similar parts throughout the several views.

In carrying out my invention, I employ an ordinary electric bell ringing apparatus, which comprises a metallic back plate 1, magnet coils 2 and 3, a spring supported armature plate 4 having an upwardly extending bell tapper arm 4^a supported in desirable proximity to a bell 5, the usual vibrating tongue 6 supported from the armature, an adjustable contact screw 7, a contact screw supporting bracket 8, and removable cap or cover plate 9. The bell ringing apparatus is wired in the usual manner, this wiring consisting in a wire 10 which leads from one contact point of an ordinary push button 11 to a binding post 12, which is supported from the base of the plate 1, this post comprising an external cap 12^a and a screw 13, the latter passing through an opening in the plate 1 and being insulated therefrom. From the binding post 12 leads a wire 14 which connects with one pole of a battery 15, the remaining pole of said battery being connected through the medium of a wire 16 with a second binding post 17

which is connected with the base of the plate 1, but insulated therefrom.

The coils 2 and 3 are connected together and one of said coils is connected with a binding post or screw 18 through a wire 18^a, said screw passing through and being insulated from the plate 1 and being connected with the contact screw supporting bracket 8. The other coil is connected to the binding post 17. A wire 19 connects the remaining point of the push button 11 with a screw 20 which projects from and is in contact with the plate 1. Affixed to the outer face of the mechanism casing 9, is a bracket or frame 21 which has the form of two crossed yoke pieces. Through a central threaded opening of the frame 21 passes a screw 22, which on the outer side of the frame, carries an adjusting nut 23 and on the inner side of the frame a hollow diaphragm 24 of thin metal. On the inner side of this diaphragm and affixed to the outer face of the casing 9 is an insulating block 25 through which and the casing 9 extends a fixed contact pin 26, the latter being insulated from said casing. This contact pin 26 has its outer end normally adjacent to the inner face of the diaphragm 24, while the inner end of said pin is connected through the medium of a wire 27 with the outer end of the binding post screw 13.

In utilizing my device, it is obvious that the button 11 may be at the outer side of an entrance door of a house, while the bell and its ringing apparatus, may be supported at any suitable point within the house. It will also be understood that the ringing of the bell through the vibratory movement of the tapper arm 4^a, will be produced in the usual manner, by pressing the button 11 and establishing the necessary electric circuit through the battery. In case, however, the temperature of the atmosphere in a room where the bell is located, should be unduly raised through the presence of fire, it will be understood that the diaphragm 24 will expand sufficiently to produce a contact between the diaphragm and the outer end of the contact pin 26, which through the connections heretofore described and the connection between the supporting frame of the diaphragm, the casing 9 and the plate 1, will serve to establish a circuit through the battery and magnet coils, which will result

in the automatic ringing of the bell thus indicating the presence of fire or undue heat.

From the construction described, it will readily be understood that I have combined 5 with an ordinary manually operated electric bell ringing mechanism, simple and effective means for causing the bell to ring in case of fire or excessive heat in the room where the bell is located.

10 From the foregoing description, it will be seen that simple and efficient means are herein provided for accomplishing the objects of the invention, but while the elements shown and described are well adapted to 15 serve the purposes for which they are intended, it is to be understood that the invention is not limited to the precise construction set forth, but includes within its purview such changes as may be made within the 20 scope of the appended claim.

What I claim, is—

In combination with an electric bell having a battery in circuit therewith, a push

button closing said circuit and a coil casing 25 for said bell, a thermostatic circuit closer removably mounted on said casing comprising a contact adapted to extend through said casing, a thermostatic diaphragm expandible into position to close the circuit 30 through said contact, a yoke frame for said diaphragm and removably secured to said casing, and electric connections between said diaphragm and the bell ringing mechanism and said contact pin whereby the contact of the diaphragm with said pin results in closing a circuit through the battery and the coils of the bell ringing mechanism, and means for adjusting the heat controlled dia- 35 phragm for operation at different tempera- tures. 40

In testimony whereof I affix my signature in presence of two witnesses.

CHARLES E. EGAN.
